United States Patent Office

Des. 205,684
Patented Sept. 6, 1966

205,684

PACKAGED HOOP AND HOOP STICK

Donald W. Schumm, 7204 Riverton, and Doyle C. Shady,
4916 Golfview, both of Fort Wayne, Ind.

Filed Apr. 19, 1965, Ser. No. 84,873

Term of patent 3½ years

(Cl. D58—2)

Fig. 2

Fig. 3

FIG. 1 is a front, elevational view of a packaged hoop and hoop stick showing our new design;

FIG. 2 is a rear, elevational view thereof;

FIG. 3 is a side, elevational view thereof taken in a direction perpendicular to the direction along which the views of FIG. 1 and FIG. 2 were viewed (the view in the opposite direction being the same);

FIG. 4 is a top end view thereof; and

FIG. 5 is a bottom end view thereof.

We claim:

The ornamental design for a packaged hoop and hoop stick, as shown and described.
